UNITED STATES PATENT OFFICE.

GARLAND TODD THAYER, OF CHARLESTON, WEST VIRGINIA.

DESIGN FOR A RAIL-BENDER YOKE.

SPECIFICATION forming part of Design No. 34,446, dated April 30, 1901.

Application filed March 22, 1901. Serial No. 52,446. Term of patent 14 years.

To all whom it may concern:

Be it known that I, GARLAND TODD THAYER, a citizen of the United States, residing at Charleston, in the county of Kanawha and State of West Virginia, have invented and produced a new and original Design for Rail-Bender Yokes, of which the following is a specification, reference being had to the accompanying drawings, forming part thereof, and in which—

Figure 1 is a perspective view of a rail-bender yoke, showing my new design. Fig. 2 is a cross-section thereof on about line 2¹/₂ of Fig. 1. Fig. 3 is a detail end view of one of the feet of the yoke, and Fig. 4 is a detail side view of one of the feet.

As shown in the drawings, the yoke is formed like an arch, curved from end to end on a gradual curve approximating the arc of a circle, with the main curved portion having the central cylindrical portion A and the ribs B, leading from the opposite sides thereof, and

having the flanges C at its upper edges, such flanges merging in the cylindrical portion A and tapering gradually toward the hooked feet D, so the yoke presents in plan the appearance of gradually diminishing in width toward its opposite ends. The hooked feet D extend laterally on the same side of the yoke, and a bead E extends around the outer side of the hooks, and thence along the ribs B, merging in the latter at D', as shown.

Having described my invention, what I claim as new, and desire to secure by Letters Patent, is—

The design for a rail-bender yoke, as herein shown and described.

In testimony whereof I have signed my name to this specification in the presence of two subscribing witnesses.

GARLAND TODD THAYER.
